[57] **CLAIM**

The ornamental design for a front face exterior of steering wheel, as shown and described.

DESCRIPTION

FIG. 1 is a front perspective view of a front face exterior of steering wheel according to our novel design; and,

FIG. 2 a left-front perspective view of a front face exterior of steering wheel according to our novel design.

The broken line illustrations are for purposes of showing the environment and are not part of the claimed design.
